UNITED STATES PATENT OFFICE.

JULIUS WEGNER, OF NEW YORK, N. Y., ASSIGNOR TO SPADONE MACHINE CO., A CO-PARTNERSHIP CONSISTING OF HENRY SPADONE AND WALTER W. SPADONE.

EXPANSION FEED ROLLER.

1,402,726.

Specification of Letters Patent.

Patented Jan. 3, 1922.

Application filed March 3, 1921. Serial No. 449,586.

To all whom it may concern:

Be it known that I, JULIUS WEGNER, a citizen of the United States, and resident of the borough and county of Queens, city and State of New York, have invented certain new and useful Improvements in Expansion Feed Rollers, of which the following is a specification.

My invention relates to feed rollers and more particularly to feed rollers for feeding webs of material and has for its object to provide a simplified and efficient construction whereby the diameter of said roller, either throughout its entire length or at any one or more points thereof, may be increased or diminished within certain limits. It is very often the case, because of unevenness in the dimensions of a given web of material due to stretch or shrinkage thereof, to feed such webs uniformly in a lineal direction. For instance, in the case of fabric impregnated with rubber or similar material for use, for instance, in constructing rubber hose and pneumatic tires and commonly called frictioned duck, it very often happens that this fabric comes from the calendar rolls either stretched or shrunken at one or both longitudinal edges and more usually at one edge thereof. When this is so, difficulty is encountered in properly feeding such material, for instance through a cutting machine of the type shown, for instance, in the Bolton Patent No. 942,164 of December 7, 1909, with the result that the resulting cut sections of said material are uneven and not uniform. The particular purpose of my invention is to overcome these objections and difficulties and to provide a feed roller which is especially adapted for use in fabric cutting machines of the type referred to hereinbefore, but which may be useful also in other fields. My invention will be fully described hereinafter and the features of novelty will be pointed out in the appended claims.

Reference is to be had to the accompanying drawings which, for the purposes of illustration and explanation, show an example of my invention without defining its limits and in which Figure 1 is an elevation of my improved roller partly in section; Fig. 2 is an end view thereof and Fig. 3 is a cross-sectional view on the line 3-3 of Fig. 1.

For the purposes of describing the invention, it will be assumed that it is applied to a feed roller only at one end thereof, it being understood that this is only an example and that the device may be duplicated or located only at the other end of the roller or at intermediate points thereof. The roller 10 may be of any desired dimensions and constructed of any suitable material and, as shown, is mounted upon a shaft 11 by means of spiders 12, the shaft 11 being journaled in bearings 13 forming part of a support which, in the present instance, is shown in the form of a frame 14. The roller 10 is split at one end at intervals throughout its circumference, as indicated in Fig. 3, the splits 15 extending from said one end inwardly and terminating, for instance, in proximity to one of the spiders 12 whereby a series of segments 15^a are formed, as shown in Fig. 1. The device whereby the diameter of the roller is varied at the split end comprises a series of members 16 located within the roller and each connected with one of the split segments of said roller, for instance by means of rivets or similar fastening devices 17. The members 16 extend radially inward from the inner surface of the roller and have their inner ends formed with bearing members 18 movably located between an annular flange 19 and a collar 20 fixed on a preferably reduced portion of the shaft 11. The members 16 are further formed with arms 21 which diverge outwardly toward the end of the roller and engage the inwardly converging surface of an operating cam member 22, the angles of inclination of the arms 21 and the converging surface of the cam member 22 being substantially identical, as illustrated in Fig. 1. The cam member 22 is slidably mounted on the aforesaid reduced portion of the shaft 11 and is provided preferably with plates 23 removably secured in position by means of bolts 24 and projecting over the arms 21. The cam member may be actuated in any suitable manner to perform its functions; as illustrated, the operating mechanism may comprise a rod 25 which extends into and is slidable lengthwise of an axial recess 26 formed in the shaft 11, as shown in Fig. 1. The rod 25 is connected with the operating cam member 22 by means of a projection 27 which extends through a slot 26^a formed in the shaft 11 and of sufficient length to per-

mit the necessary operative movements of the parts without interference. At its outer end, which is located exteriorly beyond the shaft 11, the rod is pivotally and rotatably connected at 28 with a fork 29 forming part of or carried by a hand lever 30 preferably provided with a handle 31 to facilitate the manipulation thereof. The lever 30 is pivoted at 32 upon a bracket 33 which is fixed upon the frame 14 and in its preferred form carries an indicating pointer or the like 34 movable in an arc adjacent and in co-operative relation to a scale plate 35 rigidly mounted upon said frame 14, as shown in Fig. 1. The scale plate may be provided with any suitable designations to indicate, for instance, the extent of expansion or contraction in the circumference of the roller 10 which follows an operation of the device under discussion and further may be provided on its rear face with notches located in registry with the designations referred to and adapted for co-operation with a suitable projection on the lever 30 to fix the same in an adjusted position; the scale plate, in addition, may be provided with suitable signs such as plus and minus, to visibly indicate the direction in which the lever 30 must be operated to produce expansion or contraction respectively in the circumference of the roller 10.

In practice, the parts normally occupy the positions shown in Fig. 1, which may be termed the neutral position and in which the roller is of even diameter throughout or, in other words, is of normal diameter at the end where the expanding device is located in the illustrated form. If the web of material which is being fed over the roller has become stretched along that edge which passes over and in proximity to the split end of the roller 10, the lever 33 is pivotally moved to shift the pointer 34 toward the left in Fig. 1 to a predetermined designation upon the scale 35. This causes the upper end of said lever 30 to move toward the right in Fig. 1 and to correspondingly shift the rod 25 in and relatively to the shaft 11. The projection 27 partaking of this sliding movement of the rod 25 consequently slides the operating cam member 22 also to the right in Fig. 1 and exerts a camming action upon the arms 21 whereby the latter are forced radially outward and by similarly moving the split segments 15^a increase the diameter of the roller at said end to the extent indicated by the designation on the scale to which the pointer 34 has been shifted. This increase in the diameter of said roller is sufficient to take up or compensate for the increased length or stretch of the web at the edge thereof and consequently brings about a perfectly straight and even feed of the fabric. If a contraction or a reduction of the diameter

of the roller 10 is desired, the handle 31 is moved to the right in Fig. 1, thereby swinging the upper end of the lever 30 to the left in said figure and withdrawing the rod 25 somewhat from the recess 26 and carrying the projection 27 along. The operating cam member 22, as a result of this, is also moved upon the shaft 11 toward the left in Fig. 1 and thereby permits the members 16 and their arms 21, under the inherent resiliency of the segments 15^a of said roller, to move radially inward. If the desired contraction in the circumference of the roller is beyond its normal diameter, the plates 23, by reason of a continued movement toward the left of the member 22, will exert a pressure upon the arms whereby said members 16 will be moved inwardly to a greater extent to reduce the diameter of said roller a distance corresponding to the designation to which the pointer 34 has been moved. The latter operation is required if, for any reason, the fabric is shrunken along the aforesaid edge or, in other words, is of lesser lineal length than the body thereof; this difference is taken up and compensated for by the aforesaid reduction in the roller's circumference.

The device is simple in construction and efficient in operation, and requires no skilled attention either in its operation or in its installation. While the invention is particularly useful in connection with cutting machines of the type referred to hereinbefore and which are commonly termed bias cutters, it will be apparent that said invention may find utility in a great many other fields. The description and illustration are, therefore, to be taken merely as an example and are not to be construed as defining the limits of said invention.

Various changes in the specific construction shown and described may be made within the scope of the claims without departing from the spirit of my invention.

I claim:

1. The combination of a roller split at intervals in an axial direction to form independent segments comprising integral extensions of the main body of said roller, a shaft carrying said roller, means having a fixed connection with said segments and mounted upon said shaft so as to be radially movable relatively thereto, and means movable lengthwise of said shaft whereby said first means is actuated radially to concurrently adjust said segments on their points of connection with the main body of said roller in directions toward and away from said shaft.

2. The combination of a roller provided at its one end with a plurality of inwardly extending splits forming a series of elastic segments comprising integral extensions of the main body of said roller, a shaft carrying said roller, a plurality of members each

- having a fixed connection with one of said segments and mounted upon said shaft so as to be radially movable relatively thereto, an operating member slidably mounted on said shaft, co-operating means on said operating member and on said plurality of members whereby the latter are coincidentally actuated in radial directions to adjust said segments in a manner to provide a progressive variation in the outer circumference of said rollers from the fixed ends of said segments to the free ends thereof and manually operated means whereby said operating member is actuated.
- 5 3. The combination of a roller provided with a plurality of splits at its one end to form a series of resilient segments comprising integral extensions of the main body of said roller, a shaft carrying said roller, 10 members secured to said segments and mounted upon said shaft so as to be radially movable relatively thereto, outwardly diverging arms on said members, an operating member slidably mounted upon said shaft and co-operating with said arms to radially adjust said members whereby said segments are adjusted to provide a progressive variation in the outer circumference of said roller
- 15 from the fixed ends of said segments to the free ends thereof and means including a pivoted lever mounted externally of said roller for shifting said operating member.
4. The combination of a roller provided with a plurality of splits at its one end to form a series of elastic segments, a shaft 35 carrying said roller, members secured to said segments and mounted upon said shaft so as to be movable radially relatively thereto, outwardly diverging arms carried by said members, a cam member slidably 40 mounted on said shaft and having an inwardly converging surface co-operating with said arms to radially move said members whereby said segments are adjusted to vary the outer circumference of said roller, 45 a rod slidable lengthwise of said shaft, a connection between said rod and said cam member, a pivoted lever connected with said rod for shifting the same to operate said cam member, a fixed scale and a pointer on 50 said lever co-operating with said scale to indicate the extent of movement of said lever.

In testimony whereof I have hereunto set my hand.

JULIUS WEGNER.
